UNITED STATES PATENT OFFICE.

PHILIPPO L. E. DEL FUNGO-GIERA, OF NEW YORK, N. Y.

MARINE MINE.

1,228,753.

Specification of Letters Patent.

Patented June 5, 1917.

Application filed May 11, 1916. Serial No. 96,800.

To all whom it may concern:

Be it known that I, PHILIPPO L. E. DEL FUNGO-GIERA, a citizen of Switzerland, and a resident of New York city, New York, have invented a new and useful Improvement in Marine Mines, which invention is 5 fully set forth in the following specification.

This invention relates to marine contact mines, and has for its object to provide a mine of this character which shall be absolutely safe to handle during the planting operation, but in which, when planted, the parts shall automatically assume a position 10 to be exploded upon contact with a vessel; but which parts shall automatically assume a position of safety if the mine should accidentally become adrift or should be lifted for replanting. A further object is to provide 15 a mine of this character which shall not be subjected to a rotating movement by the action of the water so as to twist the cable to which it is attached, and thereby ultimately break the same from its moorings.

20 A further object is to provide a mine of this character which shall be of such exterior configuration as to afford no opportunity for the attachment of marine growths, with consequent corrosion. Further detailed 25 objects will be hereinafter set forth, and will be apparent from the accompanying description.

With these objects in view, the invention consists in the combination of elements hereinafter described and then set forth in the 30 claims.

The inventive idea is capable of receiving a variety of mechanical expressions, some of which, for the purpose of illustrating the 35 invention, are shown in the accompanying drawings, but the same are to be taken as illustrative only, and not as defining the scope of the invention, reference being had to the appended claims for this purpose.

40 In said drawings—

Figure 1 is a vertical central section through one form of my safety contact mine;

Fig. 2 is a top plan view thereof;

Fig. 3 is a top plan view of the container 45 for the priming charge, and Fig. 3^a is a vertical central section thereof;

Fig. 4 is a central vertical section through the cylindrical chamber in which the priming charge is located;

50 Fig. 5 is a central vertical section of one

of the contact plungers for firing the priming charge on contact with the vessel and exploding the main charge of the mine; and

Fig. 6 is a central vertical section of a modified form of the invention.

Referring to the drawings, in which like reference numerals indicate like parts throughout the several views, 1 is the shell of the mine which, below the water-line, is in the shape of an inverted cone rounded at 60 its bottom, and 2 is the dome-shaped top portion of the mine normally above the water-line. Located in the dome 2 is a cylinder 3 (see Figs. 1 and 4), provided at its top portion with a radial flange 4, by means of which it is secured in a central opening in the top of the dome, and a cover 5 is placed over the outer open end thereof, and provided with suitable packing. The cylinder 3 and the cover 5 are secured in place 65 by bolts 6. This cylinder is provided with vertical slots 7, 7, extending through the walls thereof. Fitting snugly within the cylinder 3 is a cup-shaped piston 8 of steel 70 (see Figs. 1, 3 and 3^a), and fitting snugly 75 within the piston 8 is a glass cup or vessel 9. This cup is provided with a glass top 10 closely cemented thereto, and is filled with a suitable acid, such as sulfuric acid 11. Beneath the glass vessel 9, the space in the piston 8 is filled with a suitable priming charge 12, which will be detonated when the acid is 80 brought into contact therewith. This charge 85 may be any suitable priming charge, such, for instance, as a combination of dry gun-cotton, carbon, chlorate of potash and bismuth. 90

Suitably secured to the piston 8 is a piston rod 13 extending down centrally through the shell 1 and out through the bottom thereof, 95 where it is provided with a mooring ring 14 of forged steel. Where the piston rod 13 passes through the shell, there is a packing chamber 15, to prevent water from leaking into the interior of the shell, the packing 16 being preferably composed of asbestos and rubber. Projecting centrally upward from the bottom of the shell is a sleeve or cylinder 17, the piston rod 13 passing downward therethrough, and a spring 18 is located 100 within the cylinder between the top of the packing plug 15 and a collar 19 secured on the piston rod 13. The strength of the spring 18 is such that under all ordinary 105 conditions before the mine is planted, and 110

when no strain is placed upon the mooring ring 14, the piston rod 13, and with it the piston cup 8, is maintained in elevated position, for a purpose hereinafter described.

5 The contact plungers 20, of which there are a plurality arranged around the dome or cover 2, are shown in enlarged detail in Fig. 5. These contact plungers are preferably of steel, and project from the exterior of 10 the dome 2 through the wall thereof, and with their points located in the apertures or slots 7, 7 of the cylinder 3. The outwardly projecting ends of these contact plungers are provided with mushroom-shaped heads 15 21, and these heads are normally protected by glass domes 22, of sufficient strength to resist a blow of anything less than approximately 100 pounds. These glass domes 22 have outwardly projecting flanges 23, which 20 are engaged by inwardly projecting flanges on rings 24 secured to the dome by bolts 25, and are provided with suitable packing.

Surrounding the contact plungers 20 at the points where they pass through the dome 25 are suitable packing or stuffing boxes 26. Bolted to the inside of the wall of the dome are cylinders 27 provided with inwardly turned flanges 28, which fit and serve as guides for the contact plungers, and within 30 these cylinders 27 are springs 29 reacting between the flanges 28 of said cylinders and collars or pins 30 on the plungers, and serve to hold the plungers retracted with the collars in contact with the packing boxes 26, 35 the proportion of the parts being such that when the plungers are thus held retracted, their points will enter the slots 7 in the cylinder 3, and when the piston 8 is in the elevated position shown in Fig. 1, the points 40 of the contact plungers will rest against the steel wall of said piston, as shown in Fig. 1.

The piston is provided near its upper edge with slots 31, so located that when the piston is depressed, the slots will be immediately opposite the points of the contact plungers, and in order to prevent the piston from turning, which would throw the slots out of register with the points of the plungers, the piston is provided with lugs 32 (Fig. 3^a), 45 which enter slots 33 (Fig. 4). The glass cup or container 9 for the sulfuric acid is preferably provided with downwardly extending skeleton-like legs or supports 34 for sustaining the cup and preventing it from 50 bearing with too great force upon the priming charge in the steel cylinder. And the piston in turn is provided in its bottom with perforations or openings 35, thereby placing the interior of the piston in open communication with the bursting charge in the casing 55 1 of the mine.

The interior of the mine casing below the water-line is lined with liquid glass as shown at 37, to protect the charge. The bursting 60 charge 38 may consist of any suitable high

explosive, such as tri-nitro-toluol, wet gun-cotton or dynamite. Over the top of the bursting charge in the lower portion of the shell or casing is placed a protecting coating of liquid glass 39, and above this, within 70 the dome 2 and surrounding the cylinder 3, is a charge of mono-nitro-naphthalene 40.

Referring to Figs. 6 to 10 inclusive, the construction and arrangement of the parts are the same as shown in Figs. 1 to 5 inclusive (the charges, however, not being shown), with the exception of the fact that the shell or casing 1^a is cylindrical with rounded or dome-like ends, instead of conical, as shown in Fig. 1. The form shown in 80 Fig. 1 will resist hydrostatic pressure to a much greater degree than the form shown in Fig. 6, the collapsible depth of the former being 982 feet, whereas the collapsible depth of the latter is 492 feet. 85

For the purpose of preventing rotation of the mine when planted, and thereby twisting the cable, with the possible danger of rupturing the same and casting the mine adrift, the casing is provided with a vertical, radial, exterior fin welded thereto, 36 in Fig. 1 and 36^a in Fig. 6. This fin acts as a kind of rudder, preventing the mine from making more than a partial turn, and causing it to drift evenly and uniformly 95 with the tide or current without rotation.

Pins may be driven through the walls of the cylinders 27, and pass through vertical slots in the contact plungers, thereby preventing the plungers from turning, and serving as an efficient guide for the latter. 100

Operation: Before the mine is planted, and after it has been filled with the bursting charge, and the priming charge placed in position, the spring 18 serves to hold the 105 steel piston 8 in its elevated position, as shown in Fig. 1, so that the points of the contact plungers 20 enter the slots 7. In this position, there is no possibility of the contact plungers being forced against the glass 110 cup 9 containing the acid, and fracturing the same. In this condition the mine may be safely handled and planted. When the mine is planted, however, and is anchored to its retaining cable by means of the mooring 115 ring 14, the buoyancy of the mine, which, in the form shown in Fig. 1, averages about 1000 pounds when provided with a 500 pound charge, exerts a pull upon the piston rod, thereby compressing the spring 18, and lowering the piston 8 in the cylinder 3, until the glass cup 9 containing the acid is opposite the slots 7, 7, and is thus exposed to the points of the contact plungers 20. In this position, if the glass domes 22 are struck by 120 anything like a piece of floating wood or other light object, they are of such strength as to resist a blow of less than 100 pounds, and the mine will not be exploded. If, however, a contact is made therewith by a large 125 130

or heavy object, such as a vessel, one or more of the glass domes 22 are shattered, and the contact plungers 20 are driven in through the slots 7, fracturing the glass cup 9, and thus freeing the acid which, coming in contact with the priming charge, acts to immediately detonate the same, and this, in turn, detonates the mono-nitro-naphthalene in the upper or dome portion of the casing and substantially simultaneously detonates the main charge in the lower part of the casing. The mono-nitro-naphthalene serves a double function. By its detonation, it serves to pulverize or thoroughly break up the main explosive charge in the lower portion of the casing, which charge is liable, after standing for a considerable time, to become packed in a solid mass. In addition to this, the detonation of the mono-nitro-naphthalene results in the production of a large volume of dense black smoke, heavier than air, and sufficient to completely envelop a large vessel for a considerable period of time after explosion. This serves to prevent the vessel from taking observations as to its location, and hampers rescue work and repairing.

If, after the mine is planted, it should be desired to take up the same for the purpose of replanting or removing it, or in case it should accidentally become adrift, the spring 18, acting on the piston rod 13, immediately elevates the piston 8, thereby again shielding the glass vessel containing the acid, and bringing the steel walls of the piston opposite the points of the contact plungers, thus rendering the mine secure against explosion.

It will be understood that the casing is of metal such, for example, as wrought steel, and it will be observed that the exterior surface is substantially free from projections or angles which would afford an anchorage or attaching place for marine growths. The exterior surface is galvanized.

It will be apparent that that part of my invention which relates to the association of a charge of mono-nitro-naphthalene with a bursting charge is of equal application whether the mine be stationary or be a moving mine such, for example, as a traveling torpedo; it is therefore to be expressly understood in this connection that the term "mine" in the definition of this invention is to be construed broadly and generic to all mines whether movable or stationary.

It will be understood by those experienced in the art that various changes and modifications may be made without departing from the spirit of the invention. Thus, it will be apparent that other suitable types of primers may be employed than that specifically described so long as such primer is adapted to be fired by inward movement of the contact plungers when the piston carrying the priming charge is lowered to the proper position. The invention has been

herein described with some particularity, in order that the same might be understood, but such particular description must not be taken as defining the limits thereof.

What is claimed is:

1. In a mine, a bursting charge incased in liquid glass. 70
2. In a mine, the combination of a bursting charge, a priming charge and a charge of mono-nitro-naphthalene. 75
3. A mine comprising a vertically elongated casing containing a bursting charge, a charge of mono-nitro-naphthalene and firing mechanism, and a vertically elongated fin projecting radially from said casing and extending longitudinally thereof throughout the major portion of its length. 80
4. In a mine, a casing, a contact plunger having an end projecting exteriorly of said casing, and a housing of frangible material secured to said casing and inclosing said projecting end, whereby said housing must be broken before said projecting end may be engaged and actuated. 85
5. In a mine, a casing, a contact plunger having an end projecting exteriorly of said casing, and a dome-shaped housing of glass secured to said casing and inclosing said projecting end, whereby said housing must be broken before said projecting end may be engaged and actuated. 90
6. A mine having a bursting charge and a charge of mono-nitro-naphthalene. 95
7. In a mine, the combination of a casing, a bursting charge therein, a piston in a cylinder within the casing, said cylinder having an aperture in its lateral wall, a piston rod projecting outward through the casing, a spring acting against said rod, a priming charge carried by said piston, a firing plunger adapted to fire said priming charge through said aperture in one position of said piston, and an anchoring cable connected to said piston rod, whereby the buoyancy of the mine serves to move said priming charge into firing position. 100
8. In a mine, a casing, a bursting charge of high explosive within the lower part of said casing, a cylinder depending from the top of said casing and within the same, a piston moving within said casing, a chemical priming charge carried by said piston, a contact firing pin or plunger projecting outward through said casing and having its firing point projecting into an aperture in said cylinder, a piston rod secured to said piston and extending downward through the bursting charge and outward through the bottom of said casing, a spring normally holding said piston elevated, and means for connecting an anchoring cable to said rod, whereby the priming charge is brought opposite the firing pin or plunger by the pull on the piston rod due to the buoyancy of the mine. 115
9. In a mine, a casing, a bursting charge of high explosive within the lower part of said casing, a cylinder depending from the top of said casing and within the same, a piston moving within said casing, a chemical priming charge carried by said piston, a contact firing pin or plunger projecting outward through said casing and having its firing point projecting into an aperture in said cylinder, a piston rod secured to said piston and extending downward through the bursting charge and outward through the bottom of said casing, a spring normally holding said piston elevated, and means for connecting an anchoring cable to said rod, whereby the priming charge is brought opposite the firing pin or plunger by the pull on the piston rod due to the buoyancy of the mine. 120
10. In a mine, a casing, a bursting charge of high explosive within the lower part of said casing, a cylinder depending from the top of said casing and within the same, a piston moving within said casing, a chemical priming charge carried by said piston, a contact firing pin or plunger projecting outward through said casing and having its firing point projecting into an aperture in said cylinder, a piston rod secured to said piston and extending downward through the bursting charge and outward through the bottom of said casing, a spring normally holding said piston elevated, and means for connecting an anchoring cable to said rod, whereby the priming charge is brought opposite the firing pin or plunger by the pull on the piston rod due to the buoyancy of the mine. 125
11. In a mine, a casing, a bursting charge of high explosive within the lower part of said casing, a cylinder depending from the top of said casing and within the same, a piston moving within said casing, a chemical priming charge carried by said piston, a contact firing pin or plunger projecting outward through said casing and having its firing point projecting into an aperture in said cylinder, a piston rod secured to said piston and extending downward through the bursting charge and outward through the bottom of said casing, a spring normally holding said piston elevated, and means for connecting an anchoring cable to said rod, whereby the priming charge is brought opposite the firing pin or plunger by the pull on the piston rod due to the buoyancy of the mine. 130

9. In a mine, a casing, a bursting charge in one portion thereof, a charge of mono-nitro-naphthalene in another portion thereof, and a priming charge so positioned with 5 in the casing that when fired it causes the detonation of the mono-nitro-naphthalene.

10. In a mine, a casing, a bursting charge therein, a priming charge within the casing, means carrying said priming charge and normally urged in one direction, a contact plunger rendered inoperative by said means when moved in said direction, and means operated by the buoyancy of the mine 15 for moving said priming charge into a position rendering said contact plunger operative.

11. In a mine, a casing, a bursting charge therein, a priming charge within the casing, a piston carrying said priming charge and provided with an aperture, a contact plunger adapted to fire said priming charge

through said aperture, a spring normally urging said piston to a position wherein said aperture is out of alignment with said plunger, and means operated by the buoyancy of 25 the mine for moving said piston to align said aperture with said plunger.

12. In a mine, a casing, a bursting charge therein, a piston carrying a breakable container for a chemical, a contact plunger 30 adapted to engage and break said container in one position of said piston, a spring normally urging said piston to a position wherein said plunger can not break said container, and means operated by the buoyancy of the 35 mine for moving said piston to a position wherein said plunger may be operated to break said container.

In testimony whereof I have signed this specification.

PHILIPPO L. E. DEL FUNGO-GIERA.
